JOHN B. REILLY, OF WHITTIER, AND CHARLES H. STONE, OF BREA, CALIFORNIA.

OVERSHOT FISHING TOOL.

Application filed October 20, 1921. Serial No. 508,958.

To all whom it may concern:

Be it known that we, JOHN B. REILLY and CHARLES H. STONE, citizens of the United States, residing at Whittier and Brea, respectively, in the counties of Los Angeles and of Orange, respectively, and State of California, have invented new and useful Improvements in Overshot Fishing Tools, of which the following is a specification.

10 Our invention relates to an overshot fishing tool that is, a tool utilized for engaging and removing from the lower portions of wells and drill holes, sections of drill rods or tubes that have become broken or disengaged from the upper portion of the drill rod or tube, the principal objects of our invention being to provide a relatively simple and practical tool that may be easily and cheaply produced, and which when lowered 15 into a well or drill hole, will readily pass over the upper end of the broken section of drill rod or tube, and said tool being provided with parts that will automatically engage with the broken rod or tube so as to 20 firmly grip the same in order that it may be elevated from the well or drill hole.

25 A further object of our invention is to construct an overshot fishing tool so that it may be easily and quickly disengaged from the broken sections of tube or drill rod after the same has been elevated from the well or drill hole.

With the foregoing and other objects in view our invention consists in certain novel 30 features of construction and arrangement of parts that will be hereinafter more fully described and claimed and illustrated in the accompanying drawings, in which:

35 Fig. 1. is a vertical section taken through the center of a fishing tool of our improved construction, and showing the same positioned in a well or drill hole, and in engagement with a member that is to be removed from said well or drill hole.

40 Fig. 2. is an enlarged horizontal section taken on the line 2—2 of Fig. 1.

Fig. 3. is an enlarged horizontal section taken on the line 3—3 of Fig. 2.

45 Fig. 4. is an enlarged horizontal section taken on the line 4—4 of Fig. 1.

Fig. 5. is a perspective view of a rotatively mounted jaw carrying a ring that forms a part of our improved fishing tool.

Referring by numerals to the accompany-

ing drawings which illustrate a practical embodiment of our invention, 10 designates the body of the device, the upper end thereof being internally threaded to receive the externally threaded lower end of a tube 11 that serves as a carrier to lower the device 15 into the well or drill hole, and to remove said device and the engaged member from said well or drill hole.

The lower end of tubular member 10, is internally threaded to receive the externally 20 threaded upper end of a ring 12, the opening through which gradually increases in diameter toward its lower end in order that said ring may be readily passed over the upper end of the tube or rod that is to be 25 engaged and removed from the well or drill hole.

In order that the upper portion of the engaged member may be shifted to the center of the well or drill, a notch 13 is formed 30 in the lower end of the ring 12, and when the tool is rotated, the shoulder at the end of this notch will engage the upper edge of the tube or rod and force the same to the center of the well or drill hole.

Formed within the tubular member 10, and preferably at a point midway between its ends, is an annular shoulder 16, and positioned against the under side of said shoulder, and rigidly fixed in any suitable manner to member 10, is a notched flange 17 that is provided on its inner edge with a series of notches 18, spaced at equal distances apart, and one end of each notch being inclined to serve as a cam surface, as the flange 20 35 is variably engaged by jaws 20.

Loosely arranged within the lower portion of tubular member 10, between the ring 17 and the upper edge of ring 12, is a relatively short tubular member or ring 19 40 that serves as a carrier for a series of upwardly projecting rod or tube engaging jaws 20, and which latter are preferably formed of metal that is resilient to a certain degree.

There are the same number of these jaws 20 as there are recesses 18 in the notched flange 17, and the lower portions of said jaws are loosely connected to ring 19 by short lugs or pins 21 that project inwardly from the lower portions of said jaws into recesses 21^a that are formed in the lower portion of said ring.

The lower portions of the jaws 20 lie immediately against the outer face of ring 19, and said jaws pass through notches 22 that are formed in a horizontally disposed flange 23 which latter projects outwardly from the upper portion of said ring.

Projecting outwardly from the lower edge of ring 19 is a flange 24 upon which the lower ends of the jaws 20 rest, and the outer face of ring 19 between the flanges 23 and 24 gradually decreases in diameter toward the upper flange 23, so that when the jaws are properly positioned on said ring, they occupy slightly inclined positions, with their inner ends inset with respect to their lower ends.

Formed in flange 24 is an arcuate slot or notch 25, and seated in the tubular member 10 and projecting into said notch or slot, 20 is an opening 26, such construction providing means for limiting the rotary movement of the ring 19 and parts carried thereby, relative to the tubular body 10.

Formed in the flange 24 is a recess 27 that 25 is adapted to receive the end of a suitable tool 28 that is utilized for rotating ring 19 within the tubular body 10, and formed through tubular body 10 in the same horizontal plane with recess 27, is a short slot 29.

30 Arranged on the inclined outer face of the ring 19, and preferably in an annular groove 30 that is formed in said outer face, is a series of short horizontally disposed springs 31, each of which is secured at its 35 center by a pin or rivet 32, to the ring 19, and said springs are arranged so that their ends occupy positions between an adjacent pair of the notches 22, and consequently the free ends of said springs bear against the 40 inner faces of the jaws 20, tending to move the latter to a disengaging position.

When the fishing tool is to be inserted 45 into a well or drill hole, a tool such as 28 is engaged in recess 27, and ring 19 is rotated so that the intermediate portions of the jaws 20 bear against the edges of notched flange 17 between the notches 18 therein, and thus said jaws may be maintained in inclined positions with their upper 50 portions projecting inwardly toward the axis of the tool, the notched flange 17 constituting means, movable at will, for opposing the action of the mentioned springs and moving said jaws inwardly into an engaging 55 position.

Tubular member 11 with the tool on the lower end thereof is now lowered into the well or drill hole, and said parts are manipulated so that the tool is engaged over the 60 upper end of the drill rod or tube to be removed from the well or drill hole, and said tool is moved downward until the upper ends of the jaws 20 engage beneath the shoulder of a joint on the drill rod or tube 65 as illustrated in Fig. 1, and the parts are

now lifted from the well or drill hole. To disengage the tool from the drill rod or tube, ring 19 is rotated until the jaws 20 pass into notches 18, whereupon the free ends of springs 31 swing the jaws downwardly a short distance, consequently moving the upper ends thereof away from the shoulder on the engaged rod or tube, thereby freeing the latter from the tool.

70 A fishing tool of our improved construction is of relatively simple structure, may be easily and cheaply produced, and is very effective in performing its intended functions.

75 It will be understood that minor changes in the size, form and construction of the various parts of our improved fishing tool, may be made and substituted for those herein shown and described without departing from the spirit of our invention, the scope 80 of which is set forth in the appended claims.

85 We claim as our invention:

1. In a fishing tool, a tubular body, a ring rotatively arranged within said body, a series of jaws carried by and projecting 90 upwardly from said ring, and springs on said ring beneath said jaws.

2. In a fishing tool, a tubular body, a notched flange on the interior thereof, a member arranged for rotary movement 95 within said tubular body, and jaws carried by said rotatively mounted member, and adapted to occupy the notches within said flange.

3. In a fishing tool, a tubular body, a 100 notched flange on the interior thereof, a member arranged for rotary movement within said tubular body, jaws carried by said rotatively mounted member, and adapted to occupy the notches within said flange, and springs on said rotatively mounted member beneath said jaws.

4. In a fishing tool, a tubular member, a ring arranged for rotation therein, a series of upwardly projecting jaws pivotally connected to said ring, and means for moving 110 said jaws from engaging position.

5. In a fishing tool, a tubular member, a ring arranged for rotation therein, and a series of upwardly projecting jaws pivotally connected to said ring, and disengaging springs arranged on the rotatively mounted member beneath said jaws.

6. In a fishing tool, a tubular body, a ring arranged for rotary movement within said body, a series of upwardly projecting jaws pivotally connected to said ring, and a notch ring within said tubular body above said 120 rotatively arranged ring.

7. In a fishing tool, a tubular body, a ring arranged for rotary movement within said body, a series of upwardly projecting jaws pivotally connected to said ring, a notch ring within said tubular body above said 125 rotatively arranged ring, and means for 130

moving said jaws upwardly into the notches of said ring when the first mentioned ring is partially rotated. which the intermediate portions of said resilient jaws are adapted variably to engage.

8. In a fishing tool, a tubular member, a series of resilient jaws pivotally arranged within said tubular member and extending upwardly therein, and a flange against

10 In testimony whereof we have signed our names to this specification.

JOHN B. REILLY,
CHAS. H. STONE.
